UNITED STATES PATENT OFFICE.

LOUIS STEIN, OF CHICAGO, ILLINOIS.

ADVERTISING PORTFOLIO.

Application filed August 10, 1925. Serial No. 49,184.

The invention relates to advertising portfolios, sometimes referred to as scrap books such as are commonly used by manufacturers and dealers in preserving or conveniently arranging and handling advertising matter; and the primary object of the invention is to produce a book of this character which is of simple construction and inexpensive to manufacture, and in which the leaves of the book will lie flat or substantially so when the book is open, irrespective of the position of opening.

A further object is to provide an advertising portfolio composed of a plurality of independent units or sections to the end that the construction is simplified and hence the cost of manufacture reduced, such independent sections further lending themselves readily to use in a loose leaf binder.

The objects of the invention thus generally stated, together with further and ancillary advantages are attained by the construction and arrangement illustrated in the accompanying drawings forming part hereof, wherein:

Figure 1 is an end view of my advertising portfolio opened at a central position.

Fig. 2 is a similar view but showing the portfolio opened at a different position.

Figs. 3 and 4 are edge views showing separate steps in the operation of making the independent units or sections of the book.

Fig. 5 is a fragmentary sectional view illustrating in detail the construction of the several units and the manner in which they may be bound in loose leaf form.

My improved book or portfolio comprises generally a plurality of independent units or sections 7 each consisting of a plurality of folded sheets or folios 8 swingingly supported upon hinge members 9 adapted to be bound within a suitable cover or binder 10.

In the present instance each unit is made up of four sheets or folios 8 of a relatively heavy grade of paper upon the opposite faces of which advertising or other matter may be pasted for preservation. Of course, any other suitable number of folios may be employed as desired.

The hinge member 9 of each of the units is composed of a cloth strip 11 having the folios 8 secured thereto substantially along the median line thereof by the well known Singer stitch 12. The strip is then folded

along said median line between the folds of the strip 11 and I preferably insert a stiffening member 13 in the form of a thin strip of cardboard with a width somewhat less than the width of the strip 11 when folded as shown in Fig. 5. This stiffening member is inserted within the fold of the strip 11 and the latter pasted to opposite sides thereof, the arrangement being such that the folded portion of the hinge strip 11 extends slightly beyond the upper edge of the stiffening strip 13. Such extending portion is shown at 14 and it will be noted that it constitutes a flexible connection between the relatively stiff sheets or folios and the stiff portion of the hinge member proper, thus allowing the group of folios in each section to swing from one side of the vertical plane of the hinge member to the other as clearly shown in Fig. 5.

The hinge member 9 further comprises, preferably, stiffening and spacing members 15 and 16 glued to opposite sides of the folded cloth strip 11. These members 15 and 16 are preferably of a width somewhat less than the width of the inner stiffening member 13 and preferably are beveled inwardly at their upper ends as shown at 17 so as to space the adjacent units a short distance apart at their upper edges.

The individual units or sections may be bound together in any desired manner to form the complete book or portfolio, but due to the independent nature thereof, they lend themselves readily to binding in loose leaf form. Thus I have shown the binder 10 as provided with spaced upright members 18 between which the hinge members 9 of the several units may be placed in side by side relation and bound together by any of the usual loose leaf fastening devices such for example as the screws 19 and sleeve member 20. It will, of course, be understood that the units are provided with holes at longitudinally spaced points in the hinge members 9 to receive the sleeve member 20.

The construction thus provided enables the portfolio to be manufactured with facility. The independent character of the several units or sections is of primary importance from the standpoint of manufacture, because it enables each group of sheets or portfolios to be secured to its hinge member without interference by the adja-

cent unit. According to the method heretofore employed, the hinge members for the adjacent groups of folios are made from a single strip of paper or material in zigzag form, the folios being secured at the adjacent upper folded edges. This method is objectionable because the fastening of any group of sheets or folios to the hinge member is rendered extremely difficult and cumbersome owing to the presence of the previously fastened adjacent sections, it being obvious that the fastening of each group of folios becomes more difficult and cumbersome as the operation proceeds due to the fact that it is necessary to handle with the fastening of each additional group all of the previously fastened groups. The use of the flexible hinge portion between the inner stiffening strip of the hinge member 9 and the line of fold of the sheets constituting the several groups is advantageous because it enables the several sections or groups to swing relative to their hinge members without excessive strain on the latter and on the stitching.

As will be apparent from a comparison of Figs. 1 and 2, the construction enables

the book to lie flat or substantially so in any position of opening, and the provision of the spacing strips on the several hinge members renders it possible to increase the combined thickness of the leaves of the book substantially by the addition of advertising or other matter.

I claim as my invention:

The combination of a folio and an anchoring means therefor comprising a strip of thin flexible fabric, said folio being stitched directly to said strip substantially along the median line of the strip and the strip being folded upon itself along said median line, and a relatively rigid member to which the portions of the folded strip on opposite sides of said median line are secured, the upper edge of said member terminating a short distance below the line of fold so that the upper edge portion of the folded strip projecting above said member constitutes a flexible connection between the folio and the rigid portion of the strip when the latter is held stationary.

In testimony whereof, I have hereunto affixed my signature.

LOUIS STEIN.
